ALEXANDER MARTINEK, OF WORCESTER, MASSACHUSETTS, ASSIGNOR TO PRAGER CO., INC., A CORPORATION OF NEW YORK

DESIGN FOR WALL PAPER OR SIMILAR MATERIAL

Application filed March 17, 1930. Serial No. 34,918. Term of patent 3½ years.

To all whom it may concern:

Be it known that I, ALEXANDER MARTINEK, a citizen of the United States, and resident of Worcester, in the county of Worcester and State of Massachusetts, have invented a new, original, and ornamental Design for Wall Paper or Similar Material, of which the following is a specification.

In the accompanying drawing:—

The figure is a surface view of a piece of wall paper or similar material showing the design. The area within the dot and dash lines shows one complete unit of the design.

The repeats are arranged in horizontal rows, and adjacent horizontal rows are one half a complete unit offset so that the angle indicated by letter A in the complete unit corresponds with the angle B of a repeat unit in the horizontal row adjacently below.

I claim:—

The ornamental design for wall paper or similar material as shown and described.

Signed at New York, in the county of New York and State of New York this 1st day of March A. D. 1930.

ALEXANDER MARTINEK.
